INVENTOR
JOHN A. CAMPBELL
BY *M. M. Campbell*

ATTORNEYS

UNITED STATES PATENT OFFICE.

JOHN ALPHEUS CAMPBELL, OF CARBONDALE, ILLINOIS.

DOOR-SPRING.

1,343,033.

Specification of Letters Patent. Patented June 8, 1920.

Application filed May 24, 1919. Serial No. 299,492.

To all whom it may concern:

Be it known that I, JOHN A. CAMPBELL, a citizen of the United States, and a resident of Carbondale, in the county of Jackson and State of Illinois, have invented certain new and useful Improvements in Door-Springs, of which the following is a specification.

My invention relates to a door spring, and 10 more especially to a door spring and check for vehicle bodies.

The object of my invention is to provide a door spring and check adapted to be concealed within the frame of the door 15 and jamb, which will automatically tend to keep the door in a normally closed position, and limit, to a predetermined degree, its outward swing when pushed open, and lock the door in its extreme open position.

20 A further object of my invention is to provide a simple, inexpensive and efficient door spring and check for automobile and other vehicle bodies, adapted to be concealed within the frame thereof, which will 25 automatically tend to keep the door normally closed, and, when opened, limit, to a predetermined degree, its outward swing, in which extreme open position the door may be held by means of a stay, the spring 30 pressure increasing, as the door is opened, from a minimum in the closed position to a maximum in the extreme open position.

The invention comprises novel features of design, construction and arrangement 35 and combination of parts, the embodiment and application of which, illustrated and described in the drawings, specification and appended claims, is the form preferred for the purposes of illustration; but it should 40 be understood that the invention is not limited to such form and that the details and application thereof may be varied without departing from the objects and scope of the invention.

45 Reference is to be had to the drawings, forming part of this specification, in which similar reference characters indicate corresponding parts throughout the several views, and in which,—

50 Figure 1 is a fragmentary view in side elevation representing a portion of an automobile body and illustrating a door thereof, the upholstery being broken away to show the details of the door spring and 55 check and the method of attaching the same in place.

Fig. 2 is an enlarged front view of a manually operable slide employed to lock the door in its extreme open position.

Fig. 3 is a side view in section of the slide 60 shown in Fig. 2 and a portion of the frame of the door to which it is attached.

Fig. 4 is a sectional plan view of the door and jamb illustrating the door spring and check in the extreme open position of the 65 door.

Referring to the drawings, and proceeding to a detailed description of the preferred embodiment of my invention illustrated therein, the automatically closing 70 spring member of the device comprises a spiral spring 5, enveloping bars 9 and draw bar 12. A plate 8 is fastened to the frame of door 10 by means of screws 11. Connecting plate 8 and the disk 6 are bars 75 9 passing through holes in said members for the reception thereof, the bars 9 being headed at both ends to secure them to said disk 6 and plate 8. Passing through a hole in plate 6 and in disk 7, and fixed to the latter by means of heading, is a draw bar 12 provided with an eyelet in the free end thereof for the attachment thereto of one end of a cable 13. Cable 13 extends through a hole 17 in the frame of door 10 and the 80 jamb 14, and is secured under tension on the inner jamb surface by means of a nut 15 and set screw 16. Concentrically with the hole 17, and in the frame of door 10 and jamb 14, are recesses 19 and 18 respectively, 85 in which are inserted metal sleeves serving as guides for the cable 13 and as protecting means for the jamb and door frame surfaces.

The locking member of the device 90 comprises a slide 22, provided with countersunk slots 23, and a central aperture 24 consisting of a circular opening and a groove 25. The slide 22 is movably secured to the frame of door 10 by means of screws 26 fitting 100 through slots 23; and the upper edge of slide 22 is bent over to form a flange 27 to which a rod 28 is secured by means of nuts 29. The rod 28 extends upwardly through the top portion of the frame of door 10, the 105 end thereof projecting above and outside of the door, a knob 30 being fixed thereto for convenience of grasping the same with the fingers. A recess having a metal sleeve 31 fitted therein is provided, concentric 110 with the hole 32 through which rod 28 projects, for the purpose of furnishing a seat.

for the knob 30, and for protecting the upper surface of the door against wear.

The spring 5, adjusted under an initial compression, tends automatically to keep the door 10 closed. When the door is pushed open, the cable 13, being fixed at one end to the jamb 14, exerts a pull upon draw bar 12, and, disk 7 being secured thereto, moves inwardly compressing the spring 5; also, nut 21, on cable 13, simultaneously moves toward recess 20 in the frame of the door 10. The force exerted by the spring 5 tending to close the door increases proportionately with the amount of compression of the spring which becomes greater as the door is opened. The door can be swung open until nut 21 enters recess 20 and becomes seated therein when the limit of motion is reached. When the knob 30 of the locking member of the device is seated in sleeve 31, the circular opening of aperture 24 in slide 22 is in register with circular recess 20 in the door frame. This is the proper position for the slide when the door is being opened. When the limit of motion is reached, which will be when nut 21 is seated in recess 20, the door may be locked in this position by pulling up on knob 30, which will move slide 22 upwardly and bring the circular opening of aperture 24 out of register with recess 20, and well above said recess opening as the groove 25 is brought up in contact with the cable 13. The door obviously may be unlocked by pressing down on knob 30.

Having thus described my invention, I

claim as new and desire to secure by Letters Patent,

1. A device of the character described for attachment to a door and adapted to be concealed within the frame thereof having a recess therein, comprising, in combination, a spring member, means for securing one end of said spring member fixedly to the frame of the door, a flexible member, means for securing one end of said flexible member to the opposite end of said spring member and for clamping the other end of said flexible member to the adjacent wall; a stop, and means operable from without said door to lock said stop within said recess in the frame of the door to prevent said spring member from closing the door. 40

2. A device of the character described for attachment to a door and adapted to be concealed within the frame thereof having a recess therein, comprising, in combination, a spring member, means for securing one end of said spring member fixedly to the frame of the door, a flexible member, means for securing one end of said flexible member to the opposite end of said spring member and for clamping the other end of said flexible member to the jamb of the door; an adjustable stop carried by said flexible member and a sliding plate intermediate said stop and said recess in the frame of the door, operable from without said door, co-operating to limit the outward swing of said door and to prevent said spring member from closing the door. 55

JOHN ALPHEUS CAMPBELL. 60
